JACKET OR SIMILAR ARTICLE

Henry Mandelbaum, New York, N. Y.

Application March 6, 1950, Serial No. 8,342

Term of patent 3½ years

(Cl. D3—4)

To all whom it may concern:

Be it known that I, Henry Mandelbaum, a citizen of the United States of America, residing in New York city, county of New York, and State of New York, have invented a new, original, and ornamental Design for a Jacket or Similar Article, of which the following is a specification, reference being had to the accompanying drawing, forming part thereof, wherein,

I claim:
The ornamental design for a jacket or similar article, substantially as shown.

HENRY MANDELBAUM.
